(57) **CLAIM**

The ornamental design for a charging handle for firearm, as shown and described.

DESCRIPTION

FIG. 1 is a side and back isometric view of a first embodiment of a charging handle for firearm, in which the charging handle has partial serrations;

FIG. 2 is another isometric view thereof;

FIG. 3 is an enlarged top plan view thereof shown broken away for ease of illustration only;

FIG. 4 is a side and back isometric view of a second embodiment of a charging handle for firearm, in which the charging handle has full serrations; and,

FIG. 5 is an enlarged top plan view thereof shown broken away for ease of illustration only.

The portions of the design shown in broken lines are included for the purpose of illustrating environment and form no part of the claimed design.
